UNITED STATES PATENT OFFICE.

DAVID BOYD, OF LOUISVILLE, KENTUCKY.

FENCE.

SPECIFICATION forming part of Letters Patent No. 388,816, dated September 4, 1888.

Application filed May 29, 1888. Serial No. 275,493. (No model.)

To all whom it may concern:

Be it known that I, DAVID BOYD, a citizen of the United States, residing at Louisville, in the county of Jefferson and State of Kentucky, 5 have invented new and useful Improvements in Fences, of which the following is a specification.

The invention relates to improvements in fences of the cross-brace variety, the main object being to prevent both lateral and longitudinal displacement of the fence by means of the said cross-braces, which are the fence-posts; and it consists in the construction and novel combination of parts hereinafter described, 15 illustrated in the accompanying drawings, and pointed out in the appended claims.

Figure 1 of the drawings represents a perspective view of part of a fence embodying the invention. Fig. 2 represents a vertical section 20 on the line $x x$ of Fig. 1. Fig. 3 is a detail perspective view showing the upper ends of the braces detached.

In the drawings, A designates a fence-post composed of the two cross-braces B B, inclining upward from one side of the fence, and the cross-brace C, inclining similarly from the opposite side, the said braces being preferably tapered toward their upper ends. The braces B are provided with notches b' in their adjacent or facing edges at equal distances below their upper ends, and with the semi-circumferential grooves b immediately below their tops, and the brace C has a similarly-situated circumferential groove, c . The adjacent surfaces of the braces B at and below their tops are flattened, as at b^2 , so that they may lie closely together, and the brace C has its side edges inserted in the notches b' of the braces B, after which the tops of the latter are then bound tightly together by a wire, D, several turns of which are made in the semi-circumferential grooves b . The two sides or strands d d' of the wire are then twisted together or crossed on the upper side of the rider-rail G, 45 (which is arranged in the upper angle formed by the intersection of the braces,) after which one of the sides or strands, d , is carried downward, and the other side or strand, d' , is carried across and wrapped one or more times 50 around the upper end of the brace C in the circumferential groove c . The side or strand d' is then carried inward over the rider G, and

carried downward on the opposite side of the same from the side or strand d , and the two sides or strands are united and twisted firmly together below the intersection of the braces in the lower angle formed by said intersection. It will be observed that the sides or strands thus pass down on opposite sides of the rider, and also on opposite sides of the braces B B, 60 and, being united both above and below, they thus embrace the said rider, and the intersection of the braces bind them firmly together. The lower ends of the braces B are separated by having their upper ends bound in contact 65 and by insertion of the brace C below said ends, and to bind the latter brace securely in place a wire loop, E, is firmly secured around the braces B near their lower ends, in order to make the notches b' bear strongly against the 70 opposite sides of the brace C. Below the forks of the braces the strands are twisted together at intervals, leaving as many loops F between them as there are to be rails H in the fence-panel. Below the lowest of said loops one 75 strand, d , is carried to one side and wrapped tightly around the brace C near its lower end, and the other strand is carried to the other side and firmly secured to the inner side of the loop E. In this construction it must be noted that 80 each fence-post A, composed of three braces and the connecting-wires, has three points of support, which form a triangle, and will resist displacing force from all directions, and that the diagonals of the braces lie in the lines of 85 direction of both lateral and longitudinal strain, giving greater stiffness and less liability to breakage. The said posts may be made independently and under cover, and when made are set up with the feet of the braces 90 resting on the ground at suitable distances apart, and the riders inserted in the upper forks of the braces with their ends lapping under the wire D. The rails H are then inserted in the loops F, their ends lapping therein, 95 either vertically or laterally, as most convenient. The said rails and riders may be of any cheap material, such as split rails, poles, &c.

If desired, the cross-braces B may all be situated on one side of the fence; but they are preferably arranged alternately on opposite sides thereof, as thereby the lateral resistance on each side will be equal.

Obviously the weight of the panel-rails is

sustained by the upper ends of the braces, and therefore there is a tendency to spread the lower ends of the braces laterally. Therefore the lateral extensions of the strands d d' are

5 drawn taut and the lower end of the series of supporting-loops F is held rigid, thereby preventing a lateral swing of the panel-rails.

The upper ends of the braces may be bound together by a separate wire from that which is 10 employed to form the supporting-loops; but it will be understood that I preferably use a single continuous wire, as there is less danger of separation of the parts of the fence, and, further, less wire is required when a continuous 15 piece is employed.

Having described my invention, I claim—

1. The herein - described fence - post, composed of the three upwardly - tapered cross-braces B B and C , the diagonals of the cross-20 sections of which lie, respectively, longitudinally and laterally in relation to the fence, the said braces B inclining from one side of the fence and being provided with the notches b' in their adjacent edges and having their tops 25 flattened on their meeting surfaces, provided with semi-circumferential grooves b , and bound together by the wire D , and their lower ends connected by the wire loop E , and the said

brace C inclining from the opposite side of the fence and having its side edges resting in the 30 notches b' of the braces B , substantially as specified.

2. The combination, in a fence, of the cross-braces B B , provided with the flattened meeting upper ends, b^2 , the semicircular grooves b , 35 and the notches b' , the cross-brace C , having its side edges in said notches, the wire D , binding together the tops of the braces B , connecting the same with the top of the brace C and having the vertically - descending strands d d' , 40 which form the loops F below the lower fork of the braces, the wire loop E , connecting the lower portions of the braces B and connected to one strand of the wire D , the other strand being secured to the lower portion of the brace 45 C , the riders G , with their ends lapping in the upper forks of the braces below the wire D , and the rails H , with their ends lapping in the loops F , substantially as specified.

In testimony that I claim the foregoing as my 50 own I have hereto affixed my signature in presence of two witnesses.

DAVID BOYD.
